COBBLE BUNDLER

Charles W. Hawthorne, Conneautville, Pa.,
assignor to Morgan Construction Company,
Worcester, Mass., a corporation of Massa-
chusetts

Application June 6, 1945, Serial No. 597,809

6 Claims. (Cl. 242—81)

1

This invention relates to cobble bundlers, and more particularly to machines for coiling waste rods or bars in metal rolling mills and similar plants, in order to form coils or bundles which may be readily handled.

In my prior Patent No. 2,083,263 granted June 8, 1937 there is disclosed a machine comprising a horizontal rotatable arbor which extends into a casing, the latter being supported on rails for movement parallel with the arbor. The arbor is provided with a screw-thread, and the construction is such that by rotating the arbor in one direction a bundle will be formed thereon within the casing. Then by reversing the rotation of the arbor, the bundle will be forced axially from the arbor by the action of the screw-thread, pushing the casing along the rails, whereupon the bundle will be ejected laterally from the casing.

In the operation of this prior construction the bundle occasionally engages the walls of the casing so tightly that it will not be ejected automatically. In fact considerable difficulty may be encountered in removing the bundle under these circumstances.

It is accordingly one object of the invention to provide a cobble bundler of a novel construction such as to greatly facilitate the discharge of the completed bundles.

It is a further object of the invention to improve the construction disclosed in my above-mentioned prior patent by preventing the bundles from engaging the walls of the casing tightly.

It is a further object of the invention to provide a cobble bundler which can be depended upon to eject the completed bundles automatically.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a front elevation of a cobble bundler;

Fig. 2 is a sectional plan view of the machine, taken approximately on the line 2—2 of Fig. 3 with the gear box cover removed;

Fig. 3 is an end elevation of the machine, viewed as indicated by the line 3—3 of Fig. 1; and

Fig. 4 is a section taken on the line 4—4 of Fig. 1.

The embodiment illustrated comprises a horizontal rotatable arbor 10 having at one end a flange 11 which is secured to a similar flange 12 on one end of a horizontal shaft 14. This shaft is supported in spaced bearings 15—15' carried by a gear box 16 which in turn rests on a base 18. A gear 19 is secured to the shaft 14 between the bearings 15, and this gear is driven by means of a pinion 20 carried by a second horizontal shaft

2

22 parallel to the shaft 14. The shaft 22 is supported in spaced bearings 23—23' carried by the box 16. A gear 24 is mounted on the shaft 22, and this gear is driven by a pinion 26 on a shaft 27 which is connected by a coupling 28 to the shaft of a reversible electric motor 29. With this construction the arbor 10 can be rotated in either direction at a speed considerably lower than that of the motor 29. The arbor is provided on its outer surface with a helical rib 31 forming a screw-thread, which preferably has a relatively coarse lead. In the unsupported end of the arbor there is provided a slot 32 which preferably extends through the arbor diametrically and is arranged in a helix of the same hand and substantially the same lead as the screw-thread 31. For a more complete disclosure of the arbor construction reference may be had to my prior Patent No. 2,083,263.

The arbor 10 is enclosed by a casing 34 having a pair of upright side walls 35—35' spaced apart in an axial direction, a bottom wall 36, and a rear wall 37 which forms a continuation of the bottom wall. The bottom wall 36 slopes downwardly and forwardly to an opening 39 at the front of the casing, this opening extending from one side wall 35 to the other. The side walls 35 are provided with aligned openings 40—40' the arbor 10 extending through one of these openings and into the other. A heavy roller 41 is mounted within the casing 34 above the arbor 10 to force the stock into firm engagement with the arbor, the roller being carried by a horizontal shaft 42 which extends beyond the roller at each end to form trunnions which are located within vertical slots 43—43' in the side walls 35. The casing 34 is supported for horizontal movement parallel with the arbor, so that the bundles may be readily stripped from the arbor. In order to facilitate this movement the base 18 is provided with a pair of horizontal rails 45 which support four wheels 46 rotatably secured to the lower portion of the casing 34 by means of pins or shafts 47. Bumpers 49 limit the inward movement of the casing to the coiling position, and other bumpers 50 limit the outward movement of the casing to the discharge position indicated by the broken lines in Fig. 1.

As the metal rods approach the arbor 10 for coiling thereon, they are guided in such a way that the completed bundle will be relatively free from binding against the casing side walls 35. For this purpose, a guide structure in the form of a hollow frame 52 is mounted in a fixed position in front of the arbor 10. This frame 52 is provided with two side walls 53—53', a bottom wall 54, and a top wall 55, all of which converge rearwardly toward a rectangular opening 57. When the casing 34 is in the coiling position, the casing opening 39 will be directly behind and aligned with the guide opening 57, as shown in

Fig. 2. The width of the guide opening, between the rear portions of the side walls 53 thereof, is substantially less than the distance between the side walls 35 of the casing 34. As a result of this construction, the rod which is being coiled upon the rotating arbor 10 will be guided away from the side walls of the casing, and the finished bundle will fit comparatively loosely within the casing.

The operation of the invention will now be apparent from the above disclosure. With the casing 34 located at its inner or coiling position against the bumpers 49, as shown in Fig. 2, the operator will pass the front end of the rod or bar through the guide opening 57 and the casing opening 39 and insert it in the arbor slot 32. Thereupon the arbor 10 will be rotated in a counter-clockwise direction, as viewed in Fig. 4, and the rod will be wound upon the arbor, the heavy roller 41 pressing the convolutions together to provide a closely compacted bundle. The guide frame 52 will direct the rod away from the casing side walls 35 and thus prevent the bundle from wedging tightly within the casing. When the bundle is completed, the rotation of the arbor 10 will be reversed, and the threads 31 will force the bundle axially from the arbor, pushing the casing 34 along the rails 45. The bumpers 50 will stop the casing in the position indicated by the broken lines in Fig. 1, and the bundle will roll forwardly through the opening 39 under the influence of gravity, aided by the weight of the roller 41. Since the bundle fits loosely within the casing and is free from binding against the side walls, this ejection will take place automatically in a thoroughly dependable manner.

Having thus described my invention, what I claim as new and desire to secure by Letters Patent is:

1. A cobble bundler comprising a rotatable arbor, a casing enclosing the arbor and having side walls which are spaced apart in an axial direction, means to rotate the arbor to form a bundle of metal rod or the like thereon within the casing, the casing and arbor being relatively movable in an axial direction so that the completed bundle may be stripped from the arbor, and guide means for the rod as it enters the casing, the guide means providing a guide opening having a width appreciably less than the distance between the side walls of the casing to prevent the bundle from binding in the casing.

2. A cobble bundler comprising a rotatable arbor, a casing enclosing the arbor and having side walls which are spaced apart in an axial direction, means to rotate the arbor to form a bundle of metal rod or the like thereon within the casing, and stationary guide means for the rod as it enters the casing, the guide means providing a guide opening having a width appreciably less than the distance between the side walls of the casing to prevent the bundle from binding in the casing, the casing being movable in an axial direction so that the completed bundles may be stripped from the arbor.

3. A cobble bundler comprising a rotatable substantially horizontal arbor, a casing enclosing the arbor and having upright side walls which are spaced apart in an axial direction and an opening at the front of the casing, means to rotate the arbor to form a bundle of metal rod or the like thereon within the casing, stationary guide means located in front of the arbor to di-

rect the rod through the opening into the casing, the guide means providing a guide opening having a width appreciably less than the width of the casing opening, and means to support the casing for movement in an axial direction so that the completed bundles may be stripped from the arbor and ejected through the casing opening without interference with the guide means.

4. A cobble bundler comprising a rotatable substantially horizontal arbor, a casing enclosing the arbor and having upright side walls which are spaced apart in an axial direction, the casing having an opening at the front which extends from one side wall to the other, means to rotate the arbor to form a bundle of metal rod or the like thereon within the casing, stationary guide means in front of the arbor to direct the rod through the opening into the casing, the guide means including two upright guide walls which are spaced apart a distance appreciably less than that between the casing side walls, and means to support the casing for movement in an axial direction so that the completed bundles may be stripped from the arbor and ejected through the casing opening without interference with the guide means.

5. A cobble bundler comprising a rotatable substantially horizontal arbor, a casing enclosing the arbor and having upright side walls which are spaced apart in an axial direction, the casing having an opening at the front which extends from one side wall to the other, means to rotate the arbor to form a bundle of metal rod or the like thereon within the casing, a stationary guide frame in front of the arbor to direct the rod through the opening into the casing, the said frame including walls which converge rearwardly toward a substantially rectangular opening having a width appreciably less than that of the casing opening, and means to support the casing for movement in an axial direction so that the completed bundles may be stripped from the arbor and ejected from the casing opening.

6. A cobble bundler comprising a rotatable substantially horizontal arbor having a screw-thread thereon, a casing enclosing the arbor and having upright side walls which are spaced apart in an axial direction, the casing having an opening at the front which extends from one side wall to the other, stationary guide means in front of the arbor to direct metal rod or the like through the opening into the casing in order that a bundle may be formed on the arbor, the guide means providing a guide opening having a width appreciably less than the width of the casing opening, means to support the casing for movement in an axial direction in order that completed bundles may be stripped from the arbor and ejected from the casing opening, and means to rotate the arbor in one direction to form a bundle thereon and in the opposite direction to discharge the bundle axially therefrom.
